Primary Examiner — Kevin K Rudzinski*Assistant Examiner* — Kathleen L Jones(74) *Attorney, Agent, or Firm* — Quickpatents, LLC; Kevin Prince(57) **CLAIM**

I claim the ornamental design for a brace for an independent rear suspension, as shown and described.

DESCRIPTION

FIG. 1 is a bottom perspective view of a brace for an independent rear suspension, showing my new design; FIG. 2 is a top perspective view thereof;

FIG. 3 is a left-side elevational view thereof;

FIG. 4 is a right-side elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken lines showing an independent rear suspension and fasteners in FIG. 1 depict environmental matter and form no part of the claimed design.
